UNITED STATES PATENT OFFICE.

ARCHIE G. HOHENSTEIN, OF NEW HAVEN, CONNECTICUT.

STEAM-BOILER.

SPECIFICATION forming part of Letters Patent No. 759,523, dated May 10, 1904.

Application filed June 1, 1903. Serial No. 159,689. (No model.)

To all whom it may concern:

Be it known that I, ARCHIE GERRY HOHENSTEIN, a citizen of the United States, residing at New Haven, in the county of New Haven and State of Connecticut, have invented or discovered certain new and useful Improvements in Steam-Boilers, of which improvements the following is a specification.

The invention described herein relates to certain improvements in water-tube boilers, the invention being more especially directed to a construction whereby the boiler is adapted for the use of liquid fuel, as oil.

Generally stated, the invention consists in the provision within the fire-box of suitable combustion-chambers or arches formed of refractory material in which the combustion of the oil occurs, the walls of the fire-box being formed in part by heating-surfaces, the arches being designed to prevent direct impingement of the hottest flames with the water-cooled tubes until complete combustion occurs.

The invention is hereinafter more fully described and claimed.

25 In the accompanying drawings, forming a part of this specification, Figure 1 is a front elevation of my improved boiler, a portion of the casing being removed. Fig. 2 is a transverse sectional elevation of the same; and Fig. 3 is a rear elevation, a portion of the back casing being removed.

In the practice of my invention the headers 1 are extended down to a point below that at which the oil is introduced and are connected 35 at their lower ends to a distributing or equalizing box tube. The headers may be formed in two vertical sections, as shown and described in application Serial No. 159,684, filed June 1, 1903, or divided transversely by a partition 4. The lower water-chambers or headers are connected to the front ends of a series 40 of tubes 5, extending rearwardly and connected to junction-boxes 6. The rear ends of two series of tubes 7 and 8 are also connected to these junction-boxes and to the upper water-chambers or portions of the headers, as described and shown in application Serial No. 159,684, filed June 1, 1903. This arrangement of the series of tubes 5, 7, and 8 may be reversed, as shown in the application referred

to. The upper ends of the headers are connected by a series of tubes 11 with the drum 12, which is also connected to the upper ends of the downtakes 13. These downtakes extend downwardly below the fire-chamber and 55 may be either nipped together to equalize circulation, as shown in Fig. 3, or connected to an equalizing box or drum, as shown and described in application Serial No. 159,685, filed June 1, 1903. Each of the downtakes is connected by a tube 9 with the equalizing box or chamber 39 at the front of the furnace, said tubes passing below the fire-chamber and forming a water-floor therefor. The outer or end downtakes are connected by a series of 60 tubes 20 with the outer or end headers and are so arranged and connected to the headers and downtakes as to form water-walls at the sides of the boiler. A series of arches 48, formed of refractory material, are arranged 65 in a space between the tubes 5 and 9, forming a series of combustion-chambers, said arches resting upon blocks 49, hereinafter described, or, if preferred, directly upon the tubes.

As clearly shown in Figs. 1 and 3, the lower 75 ends of the headers are drawn in or flattened, so as to form spaces *a* through which can be inserted the burners 50, which project through the front casing. In case the burners are not inserted through all the spaces between the 80 lower ends of the headers such unoccupied space can be covered by pieces of mica, so as to permit the firemen to inspect the flame within the fire-chamber.

The entrance of air between the tubes 9, 85 forming the water-floor, is prevented by a plate 51, which extends from the front of the furnace to a point near the downtakes, and the open space thus formed is adapted to be closed by a hinged section 52 of the floor. 90 This hinged section or door is raised and lowered to control the flow of air through the open space by the means of a bell-crank lever and rod 53, extended to the front of the boiler. On the tubes forming the water-floor are arranged a series of metal blocks 49, made of a width approximately equal to the distance between the centers of adjacent tubes and have their under surfaces grooved, as shown in Figs. 1 and 3, to form air-passages and in- 95 100

crease the heating-surfaces of these blocks. As the air flows up through the opening adjacent to the downtakes it will flow forward along the passages in the blocks and the upper surfaces of the tubes 9, being highly heated both by the tubes and the blocks which are heated by the flame in the combustion-chambers.

It will be observed that in the construction shown the equalizing-box and the water-floors are arranged a considerable distance above the floor of the fire-room, so that there will be a free flow of air therethrough, keeping such floor cool, thereby permitting of the storage of the liquid fuel immediately below the boiler. In order to prevent the downtakes from being injured by the direct impingement of the hot flames from the combustion-chambers, their lower portions are covered by refractory material, and the space between the downtakes and the junction-boxes is closed by a supporting-wall 54, also a form of refractory material.

It is characteristic of my improved boiler that the sides, ends, and bottom of the fire-box are formed by water-walls, the headers forming the front wall, the tubes forming the side walls, the downtakes forming the rear wall, while the bottom of the fire-box is formed by the tubes 9. The refractory arches are employed for insuring complete vaporization and ignition of the gases before they come into contact with water-cooled surfaces, thus preventing the formation of carbon.

It will be observed that the headers, downtakes, side water-wall, and the water-floor form portions of the complete loop circulation characteristic of my improved type of boiler.

I claim herein as my invention—

1. A water-tube boiler having in combination a lower series of water-chambers forming the front wall of the fire-box, an upper series of water-chambers, connected series of tubes extending from said chambers, and return connections from the upper to the lower series of water-chambers, substantially as set forth.

2. A water-tube boiler having in combination a lower series of water-chambers forming the front wall of the fire-box, an upper series of water-chambers, connected series of tubes extending from said chambers, tubes extending from the lower water-chambers and forming the bottom of the fire-box, and connections from the upper series of water-chambers to said tubes, substantially as set forth.

3. A water-tube boiler having in combination headers arranged to form the front of the

fire-box, three connected series of tubes extending from the headers, tubes extending from the upper portions of the headers, downtakes having their upper ends connected to said tubes, and tubes extending forwardly from the downtakes and connected to the headers, and forming a floor for the fire-box, substantially as set forth. 60 65

4. A water-tube boiler having in combination headers arranged to form the front of the fire-box, three connected series of tubes extending from the headers, a drum connected to the upper portions of the headers, downtakes extending from the drum, and tubes extending from the downtakes and connected to the headers and forming a water-floor for the fire-box, substantially as set forth. 70

5. A water-tube boiler having in combination a distributing or equalizing box, headers connected to said box and forming the front of the fire-box, three connected series of tubes extending from the headers, a drum connected to the headers, downtakes, tubes extending from the downtakes to the equalizing-box and forming a water-floor for the fire-box, and tubes extending from the end downtakes to end headers and forming water-walls for the fire-box, substantially as set forth. 75 80 85

6. A water-tube boiler having a loop circulation having in combination therewith water-walls forming the sides, ends and floor of the fire-box and forming parts of the circulating system of the boiler, substantially as set forth. 90

7. A water-tube boiler having in combination therewith water-walls forming the sides, ends and floor of the fire-box and forming parts of the circulating system of the boiler, substantially as set forth. 95

8. A water-tube boiler having in combination therewith a water-floor for the fire-box and a series of arches or combustion-chambers supported by said floor, substantially as set forth. 100

9. A water-tube boiler having in combination therewith a water-floor formed of a series of tubes included in the circulating system of the boiler, metal blocks having grooved under surfaces resting on said tubes and arches or combustion-chambers supported by said blocks, substantially as set forth. 105

In testimony whereof I have hereunto set my hand.

ARCHIE G. HOHENSTEIN.
